UNITED STATES PATENT OFFICE.

DORSEY FROST ASBURY, OF WASHINGTON, DISTRICT OF COLUMBIA, ASSIGNOR TO UNITED STATES ORDNANCE COMPANY, OF WASHINGTON, DISTRICT OF COLUMBIA, A CORPORATION OF VIRGINIA.

POWDER-TANK CLOSURE.

1,281,892.

Specification of Letters Patent. Patented Oct. 15, 1918.

Application filed October 26, 1917. Serial No. 198,570.

To all whom it may concern:

Be it known that I, DORSEY F. ASBURY, a citizen of the United States, residing at Washington, District of Columbia, have invented certain new and useful Improvements in Powder-Tank Closures; and I do hereby declare the following to be a full, clear, and exact description of the invention, such as will enable others skilled in the art to which it appertains to make and use the same.

My invention relates to powder tank closures, and is particularly designed as an improvement of the closure illustrated and described in U. S. Letters Patent No. 1,243,974 granted to John N. Powers and Abner Y. Leech, Jr., Oct. 23, 1917.

The particular purpose of my invention is to simplify the production and materially reduce the cost of manufacture of the locking arms described and shown in the aforementioned Patent No. 1,243,974. To this end I construct the arms by stamping them from a metal blank in such manner that adjacent arms will be mutually connected between their outer and inner ends and the latter left free and spaced apart with respect to each other.

In describing my invention reference will be had to the accompanying drawing where-in like characters of reference denote corresponding parts in the several views and in which—

Figure 1 is a vertical section through a powder tank closure embodying my invention, the closure being shown in locked position;

Fig. 2, a plan view of the closure, the same being shown in unlocked position and

Fig. 3, a plan view of my improved locking arm structure detached from the closure.

Referring to the drawing 10 indicates the upper end of a powder tank and 11 the top ring carried thereby. This ring 11 is provided with an annular rib 12 over which the upper end of the tank 10 is trained to form a sealing surface 13. Provided on the ring 11 at predetermined spaced intervals are inwardly directed bearing ledges 14 for a purpose that will presently appear. While I have shown four bearing ledges 14 it will be apparent that this number can be increased according to the particular circumstances at hand. The cover element of the closure is indicated at 15 and is provided on its under

side and at its periphery with an annular groove 16 having seated therein a gasket 17 adapted to coöperate with the sealing surface 13.

The locking device for the cover 15 includes a locking arm structure of the type illustrated in Fig. 3 and which I form by stamping a plurality of locking arms 18 from a blank of spring metal so as to provide mutual connections 19 between adjacent arms slightly inward of their outer ends and leaving the inner ends of said arms free and spaced apart with respect to each other. By this process I am enabled to form all the arms necessary for a given closure with one operation and thereby both facilitate the production of such arms and materially reduce the cost of manufacture. Mounted centrally on the cover 15 is an upwardly extending threaded stud 20 which passes between the inner ends of the arms 18. Threaded on the stud 20 is a nut 21 and interposed between this nut and the arms 18 is a washer 22 whereby the rotation of the nut 21 will not produce excessive wear of the arms 18.

In applying the closure the outer ends of the arms 18 are inserted between the ledges 14 and after the gasket 17 engages the surface 12 the arms 18 are rotated so as to dispose their outer ends beneath respective ledges 14. The nut 21 is then rotated to move the same inwardly which will force the inner ends of the arms 18 in the direction of the cover and flex and energize said arms, which latter and the connections 19 then act on the cover 15 adjacent its outer edge to force the gasket 17 into effective sealing engagement with the surface 13.

I desirably provide the closure with a handle 23 whose ends are pivotally engaged in eye members 24 carried respectively by pivotally disposed arms 18 as clearly shown in Fig. 2.

What is claimed is:

1. In a powder tank closure, the combination of a sealing surface, a cover coöperating with the sealing surface, a locking member for forcing the cover into engagement with the sealing surface, said member comprising a plurality of mutually connected spring arms having their outer ends in engagement with a part of the tank body outwardly of the cover and their inner ends

free, and means acting against the inner ends of said arms to force the same inwardly and create closing pressure on the cover.

2. In a powder tank closure, the combination of a top ring, a sealing surface, a cover coöperating with the sealing surface, a locking member for forcing the cover into engagement with the sealing surface, said member comprising a plurality of spring arms each of which is mutually connected with the arms on either side thereof and having their outer ends in engagement with the top ring and their inner ends free, said mutual connections being disposed inwardly of the outer ends of said arms, and means acting against the inner ends of said arms to force the same inwardly and create closing pressure on the cover.

3. In a powder tank closure, the combination of a top ring, a sealing surface, a cover coöperating with the sealing surface, a locking member for forcing the cover into engagement with the sealing surface, said member comprising a plurality of mutually connected spring arms engaging the top ring outwardly of the cover, the connections be-

tween the arms engaging the cover and the inner ends of said arms being free, and means acting against the inner ends of said arms to force the same inwardly and create closing pressure on the cover.

4. In a powder tank closure, the combination of a sealing surface, a cover having a rim portion coöperating with the sealing surface and its central portion depressed with respect to the rim portion, locking means comprising spring arms having their inner ends free and their outer ends in engagement with a part of the tank body outwardly of the cover, and means supported by the depressed center of the cover for bending the inner portions of said arms into the space afforded by said depressed portion to thereby energize the arms and create sealing pressure on the cover.

In testimony whereof I affix my signature in the presence of two subscribing witnesses.

DORSEY FROST ASBURY.
